ABSTRACT: In combination with a relay, a driving circuit in which the relay drop in and drop out times are made equal in response to abrupt and correspondingly occurring changes of input signal level. An arrangement of active sensing and biasing elements delays the actual opening or closing of the relay by charging up a capacitor to different predetermined levels and requiring the change of state to occur well within the capacitor charging times independent of the initial closure state.

FIG. 2

RELAY DRIVER WITH AUTOMATIC TIME DISTORTION COMPENSATION

BACKGROUND OF THE INVENTION

This invention relates to a circuit for compensating for the unequal transition times occurring in a bistable remanent device such as a pulse driven magnetically actuatable relay.

It is well known that a relay is made of an electric coil surrounding a pair of magnetically responsive contact elements. The sending of current pulses through the coil controls the opening and closure of such relay contacts. Pulse control relays for example have an asymmetrical response for opening and closing of the contacts. That is, the opening and closure times are unequal.

In the prior art, the compensation and correction for this condition has been based on mechanical action. More precise solutions have included changing the electronic circuitry of the relay driver. This consists in either delaying or accelerating the operation of the pulse driven relay due to the use of energy previously stored and used during the command for supplying current to the coil of the relay. Reference is made to IBM Technical Disclosure Bulletin, Volume 11, Number 11, Apr., 1969, at page 1,403 for the description of a solenoid driver circuit in which the switching time is decreased. However, the distortion resulting from the unequal rise and fall times is still present. This lack of compensation results from the fact that the action of the correction circuit is dependent on the initial state of the relay. Restated, the compensation circuit is responsive to either the leading or trailing edge of the electric control signal and varies in its timed response as a function of the relay closure state.

It is accordingly an object of this invention to devise a circuit for compensating for the unequal transition times between the stable states in a bistable remanent device actuated by abrupt changes of input signal levels.

It is a more specific object of this invention to devise an electronic relay driver with which it is possible to obtain an automatic and symmetrical compensation for the time distortions due to the responses of the relay.

SUMMARY OF THE INVENTION

The foregoing objects are satisfied in an embodiment using a charge storage element as a part of the circuit for automatically compensating of the unequal transition times in a bistable remanent device such as a relay. The circuit includes means responsive to abrupt changes of the input signal level for charging up the storage means, and means for energizing the relay coil to change the relay state when the capacitor is charged up to a predetermined threshold.

In this invention, it is necessary to charge the storage element from a first to a second threshold level at a first time constant in response to a first input signal change. The storage element is additionally charged from a second to a third threshold level at a second time constant. The relay is actuated and completes its transition from the first to the second stable state during the second to third threshold level charging time. Similarly, the storage element is charged from the third to second threshold level at the second time constant when subjected to another abrupt input signal change, the charging continuing from the second to the first threshold level at the first time constant. The relay transition from the second to the first stable state occurs during the second to first threshold level charging time. As a consequence, the drop in-drop out relay characteristics prove quite symmetrical with this form of compensation, and occur independent of whether the relay is initially opened or closed with reference to the applied control pulse.

BRIEF DESCRIPTION OF THE DRAWINGS

FIG. 1 is a schematic diagram of the solenoid driver circuit, including the relay coil and relay contact positions.

FIG. 2, is a timing diagram of wave forms appearing at selected nodes in the circuit shown in FIG. 1.

DESCRIPTION OF THE PREFERRED EMBODIMENT

Referring now to FIG. 1 of the drawing, there is shown a circuit for driving relay coil B_0 . The relay is closed-circuited when the contact is in position B and open-circuited when the contact is in position A. The relay B_0 is pulsed open or closed when driven by an input current applied at I to the base of transistor T_1 through diode D_7 and resistor R_{10} .

Transistors T_1 , T_2 and T_4 used in the circuit for sensing and biasing are of the NPN type. They are all driven in the common emitter mode.

Now looking at the circuit construction, the collector of transistor T_1 is connected to the cathode of diode D_3 and the anode of diode D_5 . Also, the collector of transistor T_2 is connected to a positive potential source $+V$ through resistor R_4 . Transistor T_2 is biased on when potential V_b is maintained by resistive voltage dividers R_5 and R_6 . The signal at the collector of T_2 in turn drives the base of transistor T_3 . Unlike the other transistors, T_3 is of the PNP type, the emitter of which being coupled to the battery source $+V$. The collector of T_3 is connected to a test tapping point L through resistor R_7 .

A voltage divider formed from resistors R_8 and R_9 couples the collector of T_3 to the base of transistor T_4 . The collector of T_4 is loaded by the solenoid coil-relay winding B_0 .

In this invention, a capacitor stores an amount of energy proportional to the preceding switching time of the relay and to the delay in the execution of the applied command. Significantly, this circuit arrangement delays the open-close relay command over a time interval equivalent to the preceding switching time before applying the current pulse to the relay coil.

Capacitor C is coupled between ground and node E. Node E joins the anodes of diodes D_1 and D_6 together with the cathode of D_5 . Resistor R_1 couples the anode of D_5 to a node formed from the cathodes of D_1 and D_2 . D_5 and R_1 are of course coupled to the collector of T_1 .

When the relay contact is closed or in the make contact position at point B battery voltage C is applied to the anodes of diodes D_2 , D_4 and D_3 , the latter two through resistor R_3 .

Referring again to FIG. 1, assume that capacitor C is charged up to voltage V through resistors R_5 and R_{11} . Furthermore, assume that transistors T_1 , T_2 , T_3 and T_4 are nonconducting and in the absence of a driving current encoiled B_0 the relay contact is in open position A. When a positive going pulse is applied at input I, transistor T_1 becomes conductive and transistors T_2 , T_3 and T_4 go into saturation. Consequently, current is driven into coil B_0 and the relay contact moves from open position A to closed position B. In the time interval between the application of the pulse leading edge at input I, and the movement of the relay from position A to position B, diode D_4 is blocked. Capacitor C is discharged through D_1 , R_1 , T_1 with a time constant $R_1 C$ until the relay contact actually assumes position B.

Referring now to FIG. 2 of the drawing, there is shown a timing and wave form diagram relating the current and voltage wave shapes at various portions of the circuit. Thus, input I is figuratively represented as a step function leading edge applied at time t_0 . The voltage at node E (a cross-capacitor C) begins discharging with the time constant $R_1 C$. At time t'_0 (representing the closure of the relay) B, is blocked due to the back biasing of the diode by the application of battery voltage V through diode D_2 . In effect, at time t'_0 capacitor C is clamped at this discharge voltage for the duration of the input pulse at I. It should be noted, that capacitor C is discharged by an amount proportional to the time necessary for the relay to pass from an open to a closed condition.

At time t_1 , the input pulse terminates. This is equivalent to a command for opening the relay. At this time, T_1 becomes open-circuited, while T_2 is having a charge storage characteristic in effect still conducts due to a discharge path provided by conducting transistors T_3 and T_4 .

At the instant transistor T_1 is cut off and with the relay instantaneously in the closed B position, capacitor C is charged in the direction towards battery voltage V through path D_2 , R_1 and D_5 . As soon as the voltage at point E becomes equal to the voltage V_b , D_6 becomes conducting and T_2 , T_3 and T_4 are turned off. At this instant, diode D_4 is opened and capacitor C becomes charged through R_3 , D_3 and D_5 . Also C is charged through D_2 , R_1 and D_5 . Thus, C is charged with a time constant equal to $R'C$, where R' is equivalent to R_1 and R_3 all over R_1+R_3 . This charge-up pattern continues until time t_3 when the relay contact open circuits. The time interval t_3-t_2 is called the release time T_{off} .

Referring again to FIGS. 1 and 2, at the time marked T_4 , a positive going input pulse is applied at point I seeking to close the relay. At this instant T_1 becomes conducting and capacitor C becomes discharged through a pair of parallel paths. The first path is formed by D_6 , R_2 , D_3 , and T_1 . The second path is formed from D_1 , R_1 and T_4 . This discharge takes place with a time constant equal to $R'C$ where R' is equivalent to R_1 , R_2 all over R_1+R_2 .

At the instant t_5 , the charge on capacitor C approximates V_b . T_1 is conducting and this causes T_2 , T_3 and T_4 to go into such ration thereby. At this point, current is applied to the coil B_0 causing relay contact to move from the open circuit position A towards the closed circuit position B. Consequently, capacitor C goes on discharging through D_1 , R_1 and T_1 until instant t_6 . The charging path time constant for the interval between t_5 and t_6 is R_1C . Once again the interval t_6-t_5 is the relay turn-on time T_{on} and is equal to t_2-t_1 . When the relay contact reaches position B at time t_6 capacitor C is clamped at a voltage slightly less than V_b due to the biasing action of the battery +V through diode D_2 .

Except for the initial operation of the relay, all of the negative going or relay opening commands are delayed over a period T_{off} whereas all of the relay closing or positive input going pulses are delayed over a period T_{on} . This shows a perfectly symmetrical compensation for the relay response.

It should be noted, that the described compensation arrangement is not limited to either relays, or reactive loads. Any system requiring that successive transition times be made equal in response to successive stepped inputs can employ this invention.

While the invention has been particularly shown and described with reference to a relay embodiment, it will be understood by those skilled in the art that various changes in form and details may be made therein without departing from the spirit and scope of the invention.

What is claimed is:

1. A circuit for automatic compensation of unequal transition times in a bistable remanent device comprising:
50 a charge storage element;
means responsive to a first input signal for charging the

storage element from a first to a second threshold level at a first time constant, and from a second to a third threshold level at a second time constant;

means for executing the transition from the first to second stable state during the second to third threshold level charging time;

means responsive to a second input signal for charging the storage element from the third to second threshold level at the second time constant and from the second to first threshold level at the first time constant; and

means for executing the transition from the second to the first stable state during the second to first threshold level charging time.

2. A circuit according to claim 1, wherein the bistable remanent device comprises a magnetically operable relay capable of assuming either an open or closed state.

3. In combination with a device capable of assuming one of at least two stable states and responsive to the abrupt application of corresponding input signal levels, a circuit for compensating the device for the unequal transition times between the stable states comprising:

charge storage means;
means responsive to a first input signal level for charging the storage means from a first to a second threshold level at a first time constant;

means responsive to the second threshold level for energizing the device to change from a first to a second stable state, and including means for charging the storage means from the second to a third threshold level at a second time constant;

means responsive to a second input signal level for charging the storage means from the third to the second threshold level at the second time constant; and

means responsive to the second threshold level for energizing the device to change from the second to the first stable state, and including means for charging the storage means from the second to the first threshold level at the first time constant.

4. A circuit according to claim 3, wherein the first time constant is substantially less than the second time constant.

5. The device of the combination set forth in claim 3 comprises a magnetically operable relay.

6. In combination with a solenoid circuit, an arrangement for making transition time within which the solenoid drops in or drops out equal in response to abrupt and corresponding changes of input signal level comprising:

charge storage means;
means responsive to each abrupt change of the input signal level for charging up the storage means; and

means for energizing the solenoid to change its state when the storage means is charged up to a predetermined threshold.
